UNITED STATES PATENT OFFICE.

FRED JOSEPH MOSER, OF KANE, PENNSYLVANIA, ASSIGNOR TO MOSER MANUFACTURING COMPANY, OF KANE, PENNSYLVANIA, A CORPORATION OF PENNSYLVANIA.

CASING-HEAD.

1,115,717.

Specification of Letters Patent.

Patented Nov. 3, 1914.

Application filed April 11, 1912. Serial No. 690,063.

To all whom it may concern:

Be it known that I, FRED J. MOSER, a citizen of the United States, residing at Kane, in the county of McKean and State of Pennsylvania, have invented new and useful Improvements in Casing-Heads, of which the following is a specification.

This invention relates to casing heads and consists in certain improvements in the construction thereof as will be hereinafter fully described and pointed out in the claims.

More particularly the invention relates to casing heads designed to be used with gas wells. In the drilling of gas wells it is common to use a length of pipe ordinarily known as the drilling nipple which is belled out at the top. It has been common practice to remove this drilling nipple at the completion of the well putting on a new piece of casing at the upper end to which the casing head could be connected. This required the provision in advance of this extra piece of casing and inasmuch as there is usually no assurance of gas, this extra provision has often been unnecessary. In an application filed by me Feb. 8th, 1912, No. 676,255 (Patent 1,045,314 Nov. 26, 1912) I showed a casing head for use with a belled casing end. It often develops that the end of the casing is so split as to make it necessary to close the joint considerably below the top of the belled end.

One of the objects of this invention is to provide a casing head which will accomplish this purpose. More broadly considered, however, the invention is not limited to use with a belled end.

The invention is illustrated in the accompanying drawings as follows:

Figure 1 shows a central section through the casing end and casing head. Fig. 2 is a section on the line 2—2 in Fig. 1. Fig. 3 is an end elevation of a belled end casing head, the point of view being from the right or left of Fig. 1.

1 marks the casing. It has the belled end 2. The casing head 3 has the discharge openings 4—4. It is provided with an extension which projects into the end of the casing, the projection being formed as follows:—The casing head is interiorly threaded at 5 and the nipple 6 is screwed into the thread 5. A packing ring 7 is arranged on the nipple between the annular shoulders formed by the ring 8 on the lower end of

the nipple and the shoulder 9 formed on the casing head.

In placing the casing head in place in the casing, the ring 8 is screwed up sufficiently to expand the packing 7 so that the packing 60 will engage the walls of the casing to a slight extent. When this is done, the extension is forced down into the casing and the expansion of the packing 7 is completed by screwing the casing head down on the 65 nipple, the packing offering sufficient resistance to prevent the turning of the nipple. In this way, a perfect joint can be formed between the casing head and the casing and the joint extends down a sufficient distance 70 to cover any openings or cracks there may be in the upper end of the casing.

The clamp for the belled casing end is formed of the two parts 10 connected together by the interlocking ears 11 and bolts 75 12. The bolt 12 extends through the slot 13 in the lug 14 in the casing head and nuts 15 and 16 are provided below the clamp and above the lug for securing the casing head. Transverse perforated sockets 17 are also 80 arranged in the clamp pieces 10 and bolts 18 extend through these so as to clamp the parts on the casing. This clamp is similar to the clamp shown in my former application heretofore referred to.

The tubing 19 extends through the opening 20 in the casing head, the opening being at the bottom of a stuffing box 21. A washer 22 is arranged in the bottom of this box, the packing 23 is arranged over the washer, 90 a follower 24 exerts pressure on the packing, and bolts 25 extend from the follower through the lugs 26 in the casing head.

The bolts 12 have the extensions 27 which project through the clamps 28, nuts 29 being 95 provided for securing the clamp on the extensions 27. The clamp is arranged above a coupling 30 so as to secure the tubing 19. The clamp 28 is similar to the structure shown in my former application heretofore 100 referred to.

What I claim as new is:—

1. The combination of a casing end; a casing head; having a centrally located opening for a tubing and an opening 105 through the head at the side of the tubing opening; a rigid extension on the head projecting into the casing and having shoulders on its outer periphery spaced axially from each other, said extension being hol- 110

low and forming a means of communicating between the casing and the side opening in the head; a packing ring on the extension between the shoulders, and a screw connection between one of said shoulders and the extension whereby the distance between the shoulders may be reduced to crowd the ring between the extension and the casing.

2. The combination of a casing end; a 10 casing head; a rigid extension on the head projecting into the casing and having shoulders on its outer periphery spaced apart axially, said extension being hollow; a packing ring on said extension between 15 the shoulders and a screw connection between the extension and one of the shoulders adapted to be actuated by the turning of the head to reduce the distance between the shoulders whereby the ring may be crowded 20 between the casing and the extension.

3. The combination of a belled casing end; a casing head; a rigid extension on the head projecting into the casing and having shoulders on its periphery spaced apart axially, said extension being hollow; a packing ring on said extension between the shoulders; and a screw connection between the extension and one of the shoulders adapted to be actuated by the turning of the head to reduce the distance between the 25 shoulders whereby the ring may be crowded between the casing and the extension.

In testimony whereof I have hereunto set my hand in the presence of two subscribing witnesses.

FRED JOSEPH MOSER.
